(57) **CLAIM**

The ornamental design for a hair styling tool, as shown and described.

DESCRIPTION

This application claims priority to U.S. patent application Ser. No. 11/350,233 filed Feb. 7, 2006.

FIG. 1 is a perspective view of a hair styling tool showing my new design;

FIG. 2 is a top elevational view of the hair styling tool of FIG. 1.

FIG. 3 is a front elevational view thereof;

FIG. 4 is a left side elevational view thereof.

FIG. 5 is a right side elevational view thereof.

FIG. 6 is a bottom side elevational view thereof; and,

FIG. 7 is a rear elevational view thereof.

The broken lines in the drawing are for illustrative purposes only and form no part of the claimed design.
